UNITED STATES PATENT OFFICE

JOHN M. MCCLATCHIE, OF NEW YORK, N. Y., ASSIGNOR TO THE BORDEN COMPANY, OF NEW YORK, N. Y., A CORPORATION OF NEW JERSEY

COVER REPLACING DEVICE FOR CAN WASHING MACHINES

Application filed February 20, 1930. Serial No. 429,925.

This invention relates more particularly to an improvement in cover replacing devices for can washing machines.

It has been proposed heretofore to provide machines used for washing large milk cans with devices for automatically replacing the covers on the cans upon completion of the washing operations. The object of the present invention is to provide an improved cover replacing device of such construction that the covers will be properly replaced on the cans more efficiently and more accurately than has been possible with the devices heretofore provided for the purpose, and also with less danger of damage to the covers and the cans. To this end the invention resides in the improved cover replacing device hereinafter described and particularly pointed out in the appended claims.

The preferred form of the invention is illustrated in the accompanying drawings in which Fig. 1 is a vertical, longitudinal section taken along the line 1—1 of Fig. 2; Fig. 2 is a vertical, transverse section taken along the line 2—2 of Fig. 4; Fig. 3 is a vertical, longitudinal section taken along the line 3—3 of Fig. 2; and Fig. 4 is a horizontal section taken along the line 4—4 of Fig. 2.

The can washing machine with which the cover replacing device of the present invention is adapted to be associated may be of any usual or preferred construction and comprises a framework of which only the discharge end is indicated in the drawings.

During the washing operations the cans 10 are advanced intermittently in inverted position along a runway including the parallel guide bars 11 supported in any suitable manner on the frame of the machine, by suitable can advancing means including reciprocating bars

12 provided with pivoted fingers 13 which are effective during movement in the direction to advance a can but ineffective during their movement in the opposite direction. These parts operate in general in a manner usual in can washing machines and need no further description.

On completion of the can washing operations, each washed can is advanced and eventually the last pair of fingers 13 acts to push the washed can off the rear

ends of the guides or guide bars 11 and into a cradle 15 fixed on a horizontal rock shaft 16 extending transversely of the guide bars 11 just beyond the rear ends thereof.

The frame of the cradle 15 includes a base portion 17 extending along the shaft 16 and provided at its ends with collars 18 surrounding the shaft and secured thereto in any suitable manner; a longitudinal member 19, preferably of T-shaped cross section, secured at its inner end to the base portion 17 and (when the cradle is in the can receiving position) extending rearwardly to form part of a can support 20 and then in a generally upward direction for engagement by the body of an inverted can resting on the support, the outer end 21 of the member 19 being bent to extend around the edge of the lower end of an inverted can and assist in retaining the can in position on the support; and a cross-piece 22 curved to conform with the shape of the can body and secured to the member 19 at a suitable point therealong. The cradle also includes a sheet metal portion 23 forming the upper surface of the can support and also extending along the member 19 to the cross piece 22, and a flange 24 projecting upwardly from the upper surface of the portion 23 of the can support and arranged in substantially a semicircle of the proper radius to receive the top of an inverted can transferred to the cradle. It will be seen that the sheet metal is curved downwardly at the forward edge of the support 20 thus facilitating the transfer of a can 10 to the support, and that both ends of the flange 24 extend downwardly in conformity with the downward curve of the sheet at the forward edge of the support 20.

After an inverted can 10 has been deposited in the cradle 15, the cradle is swung downwardly to deposit the can in upright position on a platform 26 supported on two horizontal members 27 connecting the uprights or posts 28 at the sides of the frame. The shaft 16 is journalled in brackets 29 at opposite sides of the frame and connected at their forward ends with the corresponding uprights 28 and at their rear ends with secondary uprights 29a extending upwardly from the

platform 26; and is rocked in the desired manner by means including a sprocket wheel 30 fixed on the shaft, a second sprocket 31 at the front of sprocket 30, sprocket chain 32 connecting the sprocket 31 with the sprocket 30, a gear 33 connected with the sprocket 31 to rotate therewith, a gear 34 mounted on a transverse shaft 35 and meshing with gear 33, a pinion 36 on said shaft 35 meshing with 5 a rack 37 and held in engagement therewith by a swinging yoke 38 pivoted on said shaft 35, a pivot or pin 39 journalled in an extension of said rack and eccentrically mounted on a rotating member 40 fixed on a trans- 10 verse shaft 41 extending across the top of the frame, a worm gear 42 fixed on said shaft 41 and meshing with a worm 43 on a shaft 44, and a pulley 45 driven from any suitable source of power by means of a belt 15 46. The transverse shaft 41 is also utilized to actuate other parts of the apparatus as will be brought out hereinafter.

As each can is swung downwardly in the cradle 15 for deposit in upright position on the platform 26, its location on the platform is controlled to some extent by two horizontal bars 47 located at the left of the path of the cans (looking in the direction in which the cans are fed to the cradle) and at different 20 heights above the platform but in each case less than the height of a can body above the platform 26. These bars are positioned inwardly from the adjacent side of the frame but are supported therefrom by extensions of 25 these bars turned outwardly and attached to said frame. At the inner sides of these bars is a guide 48 in the form of a sheet of suitable material which extends above the top bar 47 and outwardly and upwardly to the 30 adjacent side of the main frame where it is attached to such frame. At the rearward side of the platform 26, improper positioning of the cans 10 is guarded against by rods 49 attached at their rear ends to a transverse 35 bar 49a connected at one end with one of the uprights or posts 28 of the main frame.

In its downward swing the outer or free end 21 of the central member of the cradle 15 passes downwardly and forwardly through a slot 50 in the platform 26 and beyond the forward edge of the platform. The can placed on the platform at this time is, however, prevented from following the cradle too far in this direction by fingers 51 projecting from the bars 47 almost to the path of the cradle and bars 52 substantially in alignment with the fingers 51 but positioned on the other side of said path of the cradle.

Before the cradle 15 swings upwardly to 60 receive another inverted can, the can which has just been placed in upright position on the platform 26 is moved transversely of the machine to a position to receive a can cover 53 (having a cylindrical portion 53a 65 adapted to fit into the neck part of the can

and a hood portion 53b) of which a plurality are supplied one by one from a runway substantially parallel to the runway along which the cans are advanced and including parallel guide bars 54 along which the covers are advanced by any suitable means, for example, means including a reciprocating bar 55 provided with pivoted fingers 56 which are effective during movement in the direction to advance a cover but ineffective during movement in the opposite direction. Such transverse movement of a can may be effected by means of a finger 57 projecting from a link of a chain 58 mounted on sprocket wheels 59 on shafts 60 journalled in brackets 61 projecting downwardly from the lower side of the platform 26. The sprocket wheels 59 are so positioned that the upper stretch of the chain will travel along a slot 62 in the platform and extending transversely of the machine; and, at regular intervals, the finger 57 will rise above the upper surface of the platform, move along the slot until it reaches the other end of the upper reach and then sink below the table to return to the other end of its effective path. As indicated in dotted lines on Fig. 4, the brackets 61 at the point at which the chain 58 rises to travel along the slot 62 are connected with a plate 62' provided with slots 62'' to receive the shanks of screws 62''', thus permitting the corresponding shaft 60 to be adjusted to tighten or loosen the chain 58 and to be secured in position to retain such adjustment.

If a can is in position on the platform 26 as the finger 57 rises above the platform, the finger will engage the can and move it transversely of the machine to a position to receive a cover from the rear ends of the guide bars 54, such receiving position being very accurately determined by the bars 52 which extend along one side of the path of movement of the can and bars 63 extending across the path of the can and supported from the main frame at the corresponding side of the machine. As here shown, each of the bars 52 is connected at one end with one of the bars 63 and at its other end with an upright 64 which may be formed integral with the bars 52. In this connection it should be noted (Fig. 3) that the finger 57 ordinarily strikes the periphery of the can somewhat to the rear of the axis and tends to impart to the can motion transverse to the machine and also motion in a direction to cause it to come into engagement with the bars 52.

While a can is in the cover receiving position, a cover is applied thereto and the can is then removed from this position by means of a finger 65 projecting from a link on a chain 66 extending around sprocket wheels 67 and 68, of which the lower 67 is positioned just below the platform 26 so that, as the finger 65 moves upwardly around said lower sprocket wheel and upwardly through a suitable

opening in the floor, said finger will engage from the inside the downwardly extending flange 69 by which the bottom 69a of the can is held above a floor or other support and thereby protected from injury, and will move the can along a runway including parallel guide bars 70 properly positioned with reference to the upper reach of the chain 66. Due to the engagement of the flange 69 at its inner side by the finger 65, the can is pulled rather than pushed by the finger and can not readily be passed along to another conveying device. To obviate this difficulty, there has been provided another finger 71 projecting from a link spaced sufficiently from the link carrying the finger 65 that the finger 71 will follow the can advanced by the finger 65, and, when the finger 65 passes around the sprocket wheel 68 and is withdrawn from engagement with the flange 69, the finger 71 will by engagement with the can from the rear advance it farther and as here disclosed deliver it upon a series of rolls 72 which may be actuated in any suitable manner.

25 The sprocket chains 58 and 66 are actuated from the shaft 41, by connections which include a gear 73 fixed on shaft 41 at the other side of the machine from the member 40 through which the cradle is actuated, a gear 30 74 meshing with the gear 73, and mounted on a shaft 75 parallel to the shaft 41, a sprocket wheel 76 mounted on the shaft 75 and connected with the gear 74 to turn therewith, a sprocket chain 76a driven by a sprocket wheel 76, a sprocket wheel 77 driven by sprocket chain 76a and mounted on the shaft 78 carrying the lower sprocket 67 for the chain 66 by which the cans are removed after the covers have been 35 applied thereto, and intermeshing bevel gears 79 for transmitting motion to the nearest shaft 60 by which the chain 58 is actuated. The upper sprocket wheel 68 for the chain 66 is also driven independently of this chain 40 by means of a sprocket chain 80 connecting a sprocket wheel 81 on the shaft 78 and a sprocket wheel 82 on a shaft 83 on which the upper sprocket 58 for the chain 66 is fixed. It should be understood that the relation between the parts is such that for each cycle of 45 operation of the finger 57 on the chain 58 there is a cycle of operation for the finger 65 on the chain 66.

50 While each can is in the cover replacing position indicated by the dot-and-dash line 84 in Fig. 4, a cover 53 is carried off the end of the cover runway, the projecting lower part of such cover enters the flared upper end of the can and the cover is then forced down 55 into the can by means which will now be described. Above the center of the cover replacing position is a vertical member or rod 85 slidably mounted in upper and lower branches of a bracket 86 secured to the main frame, and at the lower end of this rod is a member or plunger in the form of a disk 87 of sufficient weight to drive home a cover properly placed on the top of the can. Above the upper branch of the bracket 86 is a collar 88 slidably mounted on the rod 85 and held against movement off the upper end thereof by suitable means as a washer 89 placed over a reduced portion at the upper end of the rod and held against the annular shoulder, thus formed, by a nut 90 screwed on such reduced portion. Said washer 89 may be considered as a vertically movable stop connected with the plunger 87, and the collar 88 may be considered as a second vertically movable stop to engage the other from below 75 so as to be effective for positively lifting the plunger but ineffective for positive depression thereof. At opposite sides thereof the collar 88 is provided with aligned pivots 91 connected with the lower ends of links 92 85 which at their upper ends are pivoted to the outer end of an arm 93 of a bell crank 94 supported by a pivot 95 carried by a bracket 96 mounted on the main frame. The other arm 97 of the bell crank is provided at its outer 90 end with a follower 98 projecting into a cam path 99 in one side or face of a member 100 fixed on shaft 41, said cam path being of suitable shape to raise the cover driving member 87 or permit it to move downwardly in 95 proper timing with the action of the rest of the machine.

Assuming that at starting the machine, no cans have as yet been discharged from the can washing machine proper, that the cradle 100 15 is in its raised, can receiving position, and that the cover driving member or disk 87 is in raised position; the full and continued operation is as follows:—As the can which has just passed through the washing zone in inverted position reaches the rear ends of the guide bars 11 of the can runway it is shoved therefrom by a pair of fingers 13 and deposited in the cradle 15 with the open end of the inverted can resting on the support 20 110 in the space bounded by the flange 24, the body of the can embraced by the curved cross piece 22, and the bottom of the can engaged by the offset end 21 of the longitudinal member of the cradle. The cradle then 115 swings downwardly to the dotted line position of Fig. 1 depositing the can on the platform 26 and then continuing its swinging movement sufficiently to free the can. At this time the cover driving member 87 is permitted to take a cover driving movement but there may be no can in position to receive a cover and no cover in position for insertion into a can.

120 The can on the platform 26 will then be engaged by the finger 57 on the chain 58 and shoved to the left (Fig. 2) to the cover inserting position. During this movement the cradle 15 will be returned to its upright can receiving position and a second can deposited 125 130

therein and the cover driving member 87 will be raised, a cover 53 being placed in the top of the first can as soon as it reaches the cover applying position. 5 Substantially at the time the cradle 15 is swung downwardly to deposit the second can on the platform 26 the vertical member or rod 85 is permitted to move downwardly to enable the member 87 to engage the cover over 10 the first can and due to its momentum force the cover into the can.

Immediately thereafter the cradle 15 will start its return movement and the arm 93 of the bell crank 94 will be swung upwardly 15 to lift the member 87 and thereby withdraw it from the cover just driven. Before the cradle has returned far enough to interfere with the can on the platform 26, the can will be moved out of the path of the cradle by the 20 finger 57 on the chain 58 and substantially at the same time the first can, now in the cover receiving position, will be engaged by the finger 65 and moved up the guide bars 70 thus leaving the cover inserting position vacant 25 to receive the next can. Obviously this operation can be repeated indefinitely.

Although the raising and lowering of the cover driving member 87 is controlled by the cam path 99 in the member 100, the sliding 30 or lost motion connection between the rod 85 and the collar 88 is such that the member 87 is not forced down rigidly against the covers but its action is dependent upon the 35 weight of the member 87 and the rod 85 and the velocity of their movement at the time the member 87 strikes a cover. By this arrangement the danger of damage to the covers during the driving operation is very 40 much reduced.

40 What I claim as new and desire to secure by Letters Patent is:

1. In a can washing machine in which the can is discharged from the washing zone in inverted position, can inverting means receiving the can from the washing zone, a support, can transferring means for receiving the can from the can inverting means and depositing it at a cover replacing position on said support with its open end uppermost, 45 means for depositing a cover on the can in cover replacing position, a vertically movable plunger for forcing the cover into the can, and plunger controlling means for raising the plunger and controlling the downward movement thereof under the action of gravity until the plunger strikes the cover.

2. In a can washing machine in which a can is discharged from the washing zone in inverted position, can inverting means receiving the can from the washing zone, a support on which the can inverting means deposits the can with its open end uppermost, means for positively shifting said can to a cover replacing position thereby avoiding interference with the can inverting means

in connection with the inversion of another can, means for depositing a cover on the can in the cover placing position, and means for forcing the cover into the open end of the can.

3. In a can washing machine in which a can is discharged from the washing zone in inverted position, can inverting means receiving the can from the washing zone and positioning it with its open end uppermost, 70 a support at a cover replacing position, means for receiving the can from the can inverting means and positively placing it at the cover replacing position thereby clearing the can inverting means for action on another can, means for depositing a cover in the open mouth of the can including a runway from which the cover drops into the open mouth of the can, and a vertically movable plunger located over the can in the cover replacing position and arranged to operate by gravity to force the cover into the can.

4. In a can washing machine in which a can is discharged from a washing zone in inverted position, a pivotally mounted cradle having an upper position to receive the can in inverted position upon discharge from the washing zone, a platform at a lower level having a slot through which the cradle moves, means for actuating the cradle to deposit the can at a receiving position on the platform with its open end uppermost and return to upper or can receiving position, means associated with the cradle operating means to remove the can from such receiving position thereby enabling the return movement of the cradle and to place the can in a cover replacing position, means for placing a cover on said can, a plunger arranged to fall by gravity and force the cover into the can, and plunger controlling means effective to lift the plunger and to control the downward movement thereof until it strikes the cover.

5. In a can washing machine of the character described, a platform, means for receiving a can discharged from the washing zone and placing it in upright position on the platform with its open end uppermost, means for positively shifting said can to a cover replacing position thereby clearing the can inverting means for action on another can, means for depositing a cover on the can including a runway from which the cover passes directly onto the can, a plunger arranged to fall by gravity onto the cover, and plunger controlling means including a cam shaped to effect lifting of the plunger and to control the downward movement thereof until it engages the cover.

6. In a can washing machine of the character described, a platform, means for receiving a can discharged from the washing zone and placing it in upright position on the platform with its open end uppermost, means for shifting said can to a cover re-

- placing position, means for depositing a cover on the can including a runway from which the cover passes directly onto the can, a plunger arranged to fall by gravity onto
- 5 the cover to force it into the can, and plunger controlling means including a vertically movable stop connected with said plunger to move upwardly and downwardly therewith, a second vertically movable stop to engage
- 10 the other stop from below so as to be effective for positively lifting the plunger but ineffective for positive depression thereof, and actuating means for the second stop including a cam having a dwell to effect holding
- 15 of the second stop in lowered position, a lifting portion, a dwell to effect holding of the second stop in raised position to sustain the plunger, and a lowering portion to permit the plunger to act on the cover.
- 20 7. In a can washing machine in which cans are discharged one by one from the washing zone in inverted position, a can runway along which the inverted cans are fed intermittently to the discharge end, a cradle pivoted to
- 25 receive a can from said can runway while in upright position and to swing downwardly to reverse the can into upright position with its open end uppermost, a platform to receive the can when so reversed and having
- 30 a slot to permit passage of the cradle to free the same from the can, means for operating the cradle, means associated with the cradle operating means for shifting each can so delivered to the platform transversely of
- 35 said slot to clear the same before the cradle reaches the slot in its return movement and for delivering such can to a cover replacing zone, means for driving a cover into said can while the latter is in said cover
- 40 replacing zone, and means for operating said cradle and the cover driving means so that a cover inserting operation is effected at each downward swing of the cradle.
8. In a machine of the character described,
- 45 means for supporting a can in upright position, means for supplying cans to the supporting means, means for placing a cover on the can, and means for forcing the cover into the can including a reciprocating
- 50 plunger and plunger operating means including a lost motion connection whereby in the downward movement the plunger will be under direct control until it engages the cover whereupon the momentum of the plunger will
- 55 act alone to insert the cover.

JOHN M. McCLATCHIE.
